UNITED STATES PATENT OFFICE.

GEORGE H. REYNOLDS, OF MANSFIELD DEPOT, CONNECTICUT, ASSIGNOR TO THE REYNOLDS ICE MACHINE COMPANY, OF NEW YORK, N. Y., A CORPORATION OF NEW YORK.

PISTON.

No. 903,886.

Specification of Letters Patent.

Patented Nov. 17, 1908.

Original application filed October 31, 1906, Serial No. 341,391. Divided and this application filed March 25, 1907.
Serial No. 364,517.

To all whom it may concern:

Be it known that I, GEORGE H. REYNOLDS, a citizen of the United States, residing in Mansfield Depot, county of Tolland, and 5 State of Connecticut, have invented a new and useful Improvement in Pistons, of which the following is a description.

This invention relates to piston mechanism specially adapted for compression cylinders, and has special reference to compression or expansion mechanisms such as shown 10 in my application, Serial Number 341,391, filed October 31st, 1906 for improvement in ice-making machines, of which this application is a division.

Among the objects of my invention may be noted the following: To provide a piston head which will be cheap of construction, effective in operation, and incapable of corroding or rusting irrespective of whether it 15 is used for steam or liquid compression; to provide a piston head composed of parts so combined as to render the same capable of being easily taken apart for any purpose desired; and to provide a construction wherein the several materials used, or which may 20 be used, are adapted to practically universal use in connection with expansion or compression mechanisms.

With the above objects in view, and others which will be set forth during the course of 25 this description, the invention consists in the parts, features, elements, and combinations of elements hereinafter described and claimed.

In order that my invention may be clearly 30 understood, the accompanying drawing is made a part of the description, and therein in the figure is an enlarged view showing partially in elevation, and partially in section, the piston head and its rod, constructed 35 and in accordance with my invention.

Referring to the drawing, the outer end of 40 the piston-rod 1 is provided with an inclined or converging portion 2, terminating in the reduced spindle 3, screw-threaded at its outer end for the reception of the jam and holding nuts 4, which clamp the parts of the piston-head together and the latter firmly upon the end of the piston-rod against the shoulder 5, 45 formed at the juncture of the inclined portion 2 with the body of the piston-rod.

The piston-head consists of the two circular parts 6 and 7, the part 6 being provided with the slightly enlarged hub-portion 8. The part 6 is provided in its periph-

ery with the groove 9 beginning substantially midway transversely of said periphery and ending at the inside face of the part 6. The part 7 of the piston-head is provided with a similar peripheral groove 10 terminating laterally of the periphery of said part at the flat face 11, which latter extends to a reduced and elongated portion 12 extending to the inner face of the part 6, which latter has a number of threaded apertures 13 for the insertion of a removing instrument. The part 7 is also provided with the elongated hub-portion 14 centrally bored for the reception of the spindle-end 3 of the piston-rod and provided with an inclined portion 15 for co-operation with the inclined part 2 of the piston-rod. The two parts 6 and 7, when secured together as described, form 20 between them a peripheral groove in the piston-head for the reception of a piston-ring, 16 which latter consists of a two-part, substantially U-shaped clamp or holder, one part of 25 which is provided with the vertical wall 15 terminating at its outer end in the flange 16, the outer surface of which is grooved so as 30 to correspond in a measure with the wall 11 and groove 10 in the part 7. The body-part 17 of the U-shaped piston-ring extends at a 35 right-angle to the wall 15 and occupies nearly all of the peripheral groove formed in the 40 piston-head. The opposite wall 18 of the piston-ring extends parallel with the wall 15 and is provided with a flange 19, the outer 45 face of which is grooved so as to conform substantially to the groove 9 and inner face 50 of the part 6 of the piston-head. The body-part 17, of the piston-ring, is provided with one or more screw-threaded bores 20, into 55 which an instrument may be inserted for removing the parts, the wall 18 having like 60 apertures 20^a, for like purposes and the two parts holding in the groove, a ring filling in 65 two parts indicated by 21 and 22, said filling having a backing-ring 23 of leather, and under said backing-ring an expansion-band 70 indicated by 24. The ring filling 21 and 22 75 may be made of rubber, but is preferably made of bronze, the same being a material less liable to corrode or rust under any and 80 all conditions, irrespective of the purpose 85 for which the piston-head is used.

On each side of the piston-ring, and between the same and the two parts of the head, a flexible packing 25 is inserted, the same consisting of a ring or strip sufficiently 90

wide to enter the groove formed by the two parts of the piston-head in the periphery of the latter and between the same and the piston-ring, the said strips of flexible packing 5 being turned over into the groove 9 on the one side and the groove 11 on the other side of the piston-head. This packing 25 is of leather, in case the piston-head is used for cylinders for water or gas compression, or 10 will be of metal, if the piston is used for steam. From this construction, it will be clearly understood that a compact and efficacious piston-head is produced, which can be used in various connections for fluid compression, and that, according to its use, the 15 material of the several parts will be changed, as above indicated, a certain kind of material being used for gas and liquid compression, and another kind of material being 20 used for steam compression.

The piston-mechanism is herein illustrated without reference to any application which may be made of the same, for the obvious reason that my invention is not confined to 25 any use to which the piston-head may be put; but, I have found this piston-head to work admirably in connection with both the compression and expansion chambers or cylinders of the ice-making apparatus disclosed 30 in my application aforesaid.

Having thus described my invention, what I claim and desire to secure by Letters Patent is:

1. A piston-head consisting of two cylindrical portions; means for securing said portions together so as to form a peripheral groove; a two-part piston-ring seated in the groove of the said head and having between them a single peripheral groove; a filling, 35 seated in the groove of the piston-ring, consisting of two parts arranged side-by-side; and an expansion-ring between the said filling and the piston-ring.

2. A piston-head having a peripheral 40 groove; a piston-ring seated in the groove of

the head and having a peripheral groove; a filling seated in the groove of the piston-ring and composed of two parts arranged side-by-side; a packing under the filling; and an expansion-band under the packing. 50

3. A piston-head having a groove in its periphery; a piston-ring seated in the groove of the head and having a groove in its periphery, said ring being smaller than the groove in said head; packing between the 55 sides of the ring and the flanges of the head, said packing overlapping the periphery of said head; and a filling in the groove of the piston-ring.

4. A piston head composed of two parts 60 forming a groove between them; means for securing said parts detachably together; a piston ring composed of two parts forming a groove between them and seated in the groove of the head; means for detachably se- 65 curing the parts of the piston ring together; a two-part filling secured in the groove of the piston ring; and packing between the piston ring and the flanges of the head, said packing lying in the grooves of the head 70 flanges.

5. A piston-head consisting of two complementary portions having each a groove in its periphery, means for combining said portions so as to produce a cylindrical head 75 having a central peripheral groove; a piston ring composed of a plurality of cylindrical portions, one of which is right angular in cross section, the said portions being grouped within the groove of the head so as to form 80 a circumferential groove; a filling disposed in the groove of the piston ring; and an expansion band under the filling.

In testimony whereof I have hereunto signed my name in the presence of two sub- 85 scribing witnesses.

GEORGE H. REYNOLDS.
